UNITED STATES PATENT OFFICE

EDWARD L. RICH, JR., OF CATONSVILLE, MARYLAND

COMBINED MATCH AND CIGARETTE PACKAGE

Application filed April 15, 1930. Serial No. 444,527.

The invention relates to cigarette packaging and more particularly has reference to a match strip and a method of associating the same with a package of cigarettes.

One method frequently used for packaging cigarettes places the cigarettes in a jacket formed of a plurality of wrappers which are folded over the cigarette ends and sealed so as to provide a neat package. Attempts to associate matches with, or incorporate them in packages of this type have heretofore been limited because of the impractical increase in size and bulk of the packages, with a consequent non-appeal to the purchaser and also a loss of ability to stack the packages properly. Further limitations in associating matches with cigarette packages have arisen because of the possibility of the cigarettes becoming tainted due to their contact with the matches.

Recognizing the above the art has sidestepped this field and turned its attention to a separate container usually formed of leather and provided with means for securing matches therein or thereon. Into a container of this type a cigarette package such as that described is inserted. While such an expedient provides matches with a package of cigarettes it requires a separate element as the matches are not associated directly with the cigarette package but with an auxiliary container therefor. Moreover such devices are objected to by many smokers because of the bulk added to the cigarette package and the additional pocket space it requires.

The major object of this invention is the provision of a match strip and a method of associating the same with a package of cigarettes.

An equally important object of the invention is the devising of a novel match strip formed of a single piece of material and having matches formed integral therewith.

Another object of the invention is the provision of a match strip which affords a stiffening member for the package so as to prevent the crushing of the cigarette and which may be bound between the wrappers of the package.

Still another object of the invention is the designing of a match strip adapted to be bound between the wrappers of a cigarette package, the outermost wrapper adjacent the match strip being provided with an integral flap forming a cover for the matches.

Yet another object of the invention is to devise a match strip adapted to be bound between the wrappers of a cigarette package, the outermost wrapper adjacent the match strip being provided with an entirely removable portion.

A further object is the provision of a match strip, adapted to be bound between the wrappers of a cigarette package and provided with a cover for the matches.

Still a further object of the invention is the designing of a match strip adapted to be bound between the wrappers of a cigarette package and means on the match strip for securing a flap adapted to cover the matches in a closed position.

With these and other objects in view, which may be incident to my improvements, the invention consists in the parts and combinations to be hereinafter set forth and claimed, with the understanding that the several necessary elements comprising my invention may be varied in construction, proportions and arrangements without departing from the spirit and scope of the appended claims.

The invention comprehends the provision of a match strip and a method for associating the same with a cigarette package. One manner of practically effecting the concept of the invention is the designing of a match strip formed of a single piece of material which is adapted to be bound between the wrappers of a cigarette package. The invention also comprehends the formation of the outermost wrapper of the cigarette package adjacent the match strip so that a portion thereof may be partially or entirely severed therefrom so as to gain access to the matches of the strip.

In order to make my invention more clearly understood, I have shown in the accompanying drawings, means for carrying the same into practical effect without limiting the improvements in their useful applications to the particular constructions which, for the pur-

pose of explanation, have been made the subject of illustration.

In the drawings:

Figure 1 is a perspective view of a cigarette package, the outer wrapper thereof being provided with an integral cover flap adapted to be opened from the side of the package.

Figure 2 is a view similar to Figure 1 showing the flap pulled back and disclosing the match strip associated with the package.

Figure 3 is a plan view of the cigarette package shown in Figure 1.

Figures 4 and 5 are plan views of cigarette packages provided with modified forms of integral cover flaps.

Figure 6 is a plan view of a cigarette package the outer wrapper thereof being provided with a removable portion.

Figures 7, 8, 9, 10, 11, 12, 13, 14 and 15 show various embodiments of match strips employed by the invention, the match ends being formed integral with the base of the strip.

Figure 16 is a fragmental detail plan view of one of the match strips showing matches so constructed that the axes of the matches are perpendicular to the base of the strip.

Figure 17 is a sectional elevation of a match strip taken along the line 17—17 of Figure 16.

Figure 18 is a plan view of a cigarette package provided with an integral cover flap adapted to be opened from an end of the package.

Figure 19 is another embodiment of the match strip, the match ends being formed integral with the base and top of the strip.

Figure 20 is a sectional elevation of a double match pad.

Figure 21 is an end elevation of the match pad taken along the line 21—21 of Figure 20.

Figure 22 is a sectional elevation of another form of double match pad.

Figures 23, 24, 25, and 26 are plan views of match strips provided with a cover for the matches.

Figure 27 is a sectional elevation along the line 27—27 of Figure 25 and shows in detail the manner of securing the protective cover in closed position.

Figure 28 is a view similar to Figure 27 and discloses protective material on two sides of the matches.

Figures 29 and 30 disclose further embodiments of the securing means employed to hold the cover on the match strip in closed position.

Figure 31 is an end view of a cigarette package having a match strip such as any of those disclosed in Figures 7, 8, 9 and 10 associated therewith.

Figure 32 is a view similar to Figure 31 and discloses a match strip of the type shown in Figures 14 and 15 associated therewith.

Figure 33 is a sectional end elevation of a

cigarette package having a match strip associated therewith and shows in detail the positioning of the match heads.

Figure 34 is a plan view of a cigarette package showing an integral side opening cover flap formed upon a wrapper of transparent paper and means for securing the same in closed position.

Figure 35 is a view similar to Figure 1 and shows the package provided with a transparent wrapper surrounding the outer wrapper adjacent the match strip.

Figure 36 is a perspective view of a match strip provided with a match cover having advertising matter on the like provided thereon.

Figure 37 is a perspective view of a cigarette package having an integral cover flap and abrasive material positioned upon the outside of the wrapper adjacent the match strip.

Throughout the drawings, like reference numerals refer to similar parts in the different views. There is shown in the drawings a cigarette package provided with an inner wrapper 1, usually of lined tinfoil and an outer wrapper 2, the former wrapper, as disclosed in Figure 33 being adjacent to the cigarettes 3, and forming a jacket around them. The usual revenue stamp placed upon an end of the package is indicated at 49. Packages of this type are well known and may be formed in any convenient manner, the cigarettes being packed therein by any suitable method.

Positioned between the inner wrapper 1 and the outer wrapper 2 is a match strip generally designated as 4. By this construction it will be appreciated that the inner wrapper or jacket is first formed, the match strip placed adjacent to the face thereof and the outer wrapper secured around the jacket and the match strip.

From an inspection of the drawings it will be appreciated that each of the several match strips or frames 4 are formed of a single match piece or material such as cardboard, paper or other suitable materials. In Figure 7 the match strip is in the form of a frame having a base 9, sides 10 and a top 11. Provided upon the base and secured thereto in any convenient manner is a piece of abrasive material 12 employed for striking the matches.

As may be seen in Figure 16, which is a detail partial view of a match strip similar to that shown in Figure 7, the matches 13 are formed integral with the base 9, and are separate from each other. Each match is tapered outwardly with a decreasing taper so that its stem adjacent to the head is of less width than the portion of the stem adjacent the base. By this expedient each match is maintained so that its longitudinal axis is perpendicular to the base 9. As a result the matches are prevented from expanding to

wards the sides 10 of the strip and moreover they are all caused to lie in substantially the same plane. Hence a match strip construction which, as will presently appear, will lie flat between the wrappers of the cigarette package is provided.

While a construction providing matches with tapered bodies is disclosed in order that they may be maintained perpendicular to the base 9, it is to be understood that different types of matches for accomplishing this feature may be employed if desired. For example, a match having a body of uniform width and provided with a cutaway section on each of its sides directly below the head could be used if desired.

The abrasive material 12 of Figure 8, secured to the base of the match strip is provided with an opening 14 which extends therethrough and through the base of the match frame. In this opening as will hereinafter appear, there is adapted to be inserted a tab formed upon a cover for the matches so as to maintain the cover in a closed position over the match strip. It should be noted that the base of Figure 8 is cut away adjacent the abrasive material for a considerable distance. This construction clearly facilitates the opening of the package as will be herein-after described. While the construction of the match strip provided with a cut away piece adjacent the abrasive material has been shown only in connection with Figure 8, it is to be understood that this expedient may be employed with other forms of the match strip.

In Figure 9 an opening 15, similar to the opening 14 but formed only in the base of the match strip is disclosed. If desired the opening 15 may be of considerable length. By the use of such an opening the feature of the cut away piece shown in Figure 8 is provided. Of course, if desired, the opening 14 may also be elongated.

There is disclosed in Figure 10 a slightly modified form of match strip provided with the base 9 previously described, and sides 16 which project over the match heads as is clearly shown. By dispensing with the top portion of the match strip it will be appreciated that in some instances tipping of the match heads with igniting material may be facilitated.

Figure 11 discloses a match strip similar in design to that shown in Figure 10, the match strip being formed with a base and sides 17, the latter of such length as to be substantially even with the match heads.

If desired a construction providing sides 18 extending substantially to the center line of the match bodies may be employed as shown in Figure 12.

In Figure 13 a match strip provided only with a base 19 is shown, separate matches being formed integral therewith.

Figure 14 discloses a type of match strip similar to that shown in Figure 7 and provided along its base, top and one side with hinged projections 20. It should be noted that each of the hinged projections 20 is co-extensive and integral with the portion of the match strip which they adjoin. Instead of this construction, hinged tabs 21 provided at the four corners of the match strip and at the center of one of its sides may be employed.

While the hinged projections 20 and the hinged tabs 21 have been disclosed as formed integral with the match strip, it will be understood, if desired separate pieces of material may be employed for forming them. This material may be different than that forming the match strip itself, can be lighter or heavier and can be secured to the match strip in any convenient manner. When such a construction is employed the length of the material forming the separate hinged portions on the base and top of the match strip may be of a length sufficient to wrap around the sides of the package or the sides and the face thereof opposite to that upon which the match strip is positioned. Similarly the hinged portion secured to the end of the match strip may be of a length sufficient to wrap around the end of the package or the end and face opposite that upon which the match strip is positioned.

In both instances either that of the hinged projections or the hinged tabs, the match strip is placed between the wrappers of the package so that the strip is opposite a front face thereof and the projections or tabs engage the sides and the bottom of the wrapper as is clearly shown in Figure 32. This construction, it will be appreciated, further strengthens the package and prevents the crushing of cigarettes.

Disclosed in Figure 19 is a form of match strip which is positioned between the wrappers of the package so that the matches thereof are parallel to the lengthwise direction of the cigarettes in the package. Here a strip provided with a base 22, sides 23 and top 24 has a unit of matches 25 formed integral with the base, and a second unit 25' formed integral with the top, the heads of the matches being adjacent to each other. Abrasive material 12' is provided upon the base and an opening 26 is formed in the base of the frame.

While I have shown a construction in Figure 19 providing two match units, it is to be understood that one may be employed if desired without departing from the spirit of the invention. In this instance any of the constructions shown in Figures 7 through 15 could be employed by merely forming the machines 13 integral with the match strip so that their longitudinal axes will be parallel to the lengthwise direction of the cigarettes.

when the strip is positioned between the package wrappers.

Either of the match strip constructions disclosed in Figures 7 through 15 which have the matches perpendicular to the longitudinal axis of the strip are so positioned between the matches of the cigarette package that the head of each match is between two adjacent cigarettes, which for the purpose of illustration have been indicated as 3' and 3''. From an inspection of Figure 33 it will be appreciated that such an expedient allows the match strip to lie flat and in close contact with the cigarettes and the wrappers around the strip so that a neat and compact package is provided.

As it has been pointed out the match strips of Figures 11, 12 and 13 are provided with short side portions or with no side portions at all. These match strips may be positioned in a cigarette package so that the heads of the matches lie between the outermost cigarette 3' and the side of the wrapper 2. It will be appreciated that when these match strip constructions are employed a package possessing the compactness of the one shown in Figure 33 is provided.

While the match strips or frames heretofore described have been formed of a single piece of material it will be appreciated that a double match pad 35 such as that shown in Figure 20 may be provided by securing two of the match strips 4 together. If desired, of course, more than two match strips 35 may be secured together so as to form a pad having more than two layers of matches. In Figure 21 the sides of the lower match strip 4' are wider than those of the upper match strip 4 so that each match head 50 lies between two match heads 51 of the upper strip and the matches in each strip will lie in substantially the same plane as the body of the strip. Of course, other arrangements of the matches may be employed for insuring this effect.

Figure 22 shows the match strips positioned oppositely with respect to each other so that the match heads 51 of the upper strip are adjacent the ends of the match body of the lower strip. When double match pads such as those shown in Figures 20 through 22 are employed it is necessary to provide only one piece of abrasive material, this being positioned upon the upper match strip.

Although the match strips have been shown as positioned on one face of the package only, it is to be understood that a match pad either of the single strip type or the plural strip type of Figures 20 through 22 inclusive may be located on both faces of the package.

For the purpose of covering the match heads the match strip is provided with a cover flap of protective material. This flap may be formed of fireproof paper, other fire-

proof material, or any other type of material desired.

A short cover flap 27 such as that just described is shown in Figure 23 secured in any convenient manner to the top of the match frame 4 so as to cover the match heads while the match strip of Figure 24 is provided with a full cover 28 over the bodies of the matches as well as their heads.

In order to maintain the cover flap in closed position a securing tab 29 is fastened to the cover. This tab is adapted to be inserted in the square or vertically cut opening 14 formed in the abrasive material 12 and the base of the match frame, as is clearly pointed out in Figures 25 and 27. A construction similar to that of Figure 27 is shown in Figure 29 where an opening 30 of different type than that of the opening 14 is employed. It should be noted that the opening 30 is sloped so that the difficulty of inserting the tab into a square or vertically cut aperture is eliminated. It will be appreciated that either the type of opening indicated by the reference numeral 14 or the type indicated by the reference numeral 30 may be employed with any of the forms of match strip or frames without departing from the spirit of the invention or the scope of the appended claims. Moreover either type of opening may be provided in the base of the frame or the abrasive material and the base.

In some instances, especially in compliance with fire and shipping regulations, it may be desirable to provide protective covering on two sides of the match strip. Shown in Figure 28 is a cover flap 28 similar to that described, and in addition to this a second strip of covering material 28' is positioned upon the opposite side of the match frame. If desired the flap 28 may be of any material, while the covering 28' may be fireproof material, or both coverings 28 and 28' may be fireproof.

Figure 26 shows a match frame provided with a cover flap 31 which has a securing tab 32 formed integral therewith. The securing tab is inserted through an opening in the abrasive material and the base of the match frame.

Instead of providing an opening in the base of the match frame or in the base and the abrasive material in order that the securing tab of the cover flap may be maintained in closed position, a construction such as that shown in Figure 30 may be provided. A securing tab 33 similar to the tab 29 is secured to the cover flap 28 in any desired manner. The tab is of a length sufficient to be inserted under a latch member 34 which is positioned upon the base 9 of the match frame and secured thereto.

While shown associated with the match frame, it will be appreciated, as will appear, that the latch construction of Figures 27, 29

and 30 may be employed to secure a wrapper cover of the cigarette package in closed position.

For the purpose of obtaining or gaining access to the matches mounted upon the match strip 4, the front face 5 of the cigarette package shown in Figure 1 is provided with an integral flap 6, three sides of which are perforated as indicated by the reference numeral 7. A tab 8 adapted to engage the match strip, as will presently appear is positioned upon the flap 6 in any convenient manner.

By reason of the perforations 7 it will be appreciated that the cover flap 6 may be partially detached upon three sides from its connection with the face 5 and thus may be opened. This position of the cover when fully opened is clearly shown in Figure 2 where the matches are exposed to easy reach.

In Figure 4 the integral cover flap 35 has been shown as provided with an integral tab 36, the perforations 7 extending around three sides of the tab.

Another embodiment of this construction is disclosed in Figure 5 where a tab upon the cover flap is entirely omitted.

In some instances it may be desirable to form the face of the cover adjacent to the matches with an entirely removable portion. Such construction is disclosed in Figure 6 where an entirely separable portion 38 is provided with perforations 39 around all of its sides.

Figure 18 discloses a cigarette package the front face of which is provided with an integral cover flap 44 adapted to be opened from the end of the package instead of from the side of the package as shown in Figures 1 through 5. The flap 44 is provided with perforations 45 which extend around three sides thereof, the perforations of greatest length being parallel to the lengthwise direction of the package. A tab is secured to the top of the cover flap. It is to be understood that this tab may be formed integral therewith or omitted if desired. With this modification of the cover flap, it is preferable to use a match strip such as shown in Figure 19 having either a single or double unit of matches although a match strip such as any of those shown in Figures 7 through 15 may be employed.

Figure 35 discloses a cigarette package similar to that shown in Figure 1, it being covered with an outer wrapper 40 of transparent paper which covers the wrappers 1 and 2 adjacent the match strip.

In Figure 34 the transparent wrapper 40 is provided with perforations 41 so as to form an integral cover flap thereon instead of on the wrapper of opaque paper. The match strip 4 is bound between the wrappers so that it is directly adjacent the transparent paper.

While the integral cover flaps formed upon the wrappers of the cigarette packages of Figures 3, 4, 5, 18, 34 and 35 have been disclosed as being substantially rectangular in shape, it will be appreciated that other outlines may be given to the flaps without departing from the spirit of the invention or the scope of the appended claims. For example, they could be formed so as to possess a semi-circular, semi-elliptical, triangular or any geometrical outline desired. Whatever shape is given to the integral cover flap, it will be appreciated that the securing tab may be formed separately therefrom and secured thereon in any convenient manner, or it may be formed integral with the flap itself.

The removable portion 38 of the cigarette package disclosed in Figure 6 may of course be given a different shape or design from that shown. In this figure a full circular outline, full elliptical outline, any of those mentioned above or any other geometrical shape could be employed.

If desired, the match strip 4 associated with the package of Figure 34 may have advertising matter printed upon its covering 27, as of the match strip of Figure 36. When this strip is used with the package of Figure 34, it is apparent that the advertising matter on the covering will be in evidence when the integral cover flap formed upon the transparent material 40 is in place. Of course, if desired, advertising matter may be printed upon any of the coverings which may be used with any of the embodiments of the invention.

The advertising matter just described may be printed upon either or both sides of the match covering associated with the match strip and may also be printed upon the underside of the integral cover flap as well as the underside of the entirely removable portion 38 disclosed in Figure 6. As the matches of each strip form a comparatively flat surface it will be appreciated that by employing a stamp, further advertisements could be stamped directly upon the matches themselves. Should it be found desirable, of course, separate advertisements could be printed upon each match.

A slightly different embodiment of the cigarette package of Figure 1 is disclosed in Figure 37. In this instance a match strip such as that shown in Figure 7 without abrasive material is employed. A strip of abrasive material 43 is secured to the outer wrapper of the package as is clearly shown. It will be appreciated that the abrasive material may be secured to the package in any position desired.

In each of the embodiments which have been disclosed it will be appreciated that a plurality of matches are incorporated directly in the cigarette package. To obtain or gain ac-

cess to the matches the integral flap either of the side opening or end opening type, as the case may be, is severed from its connection with the face of the wrapper by merely tearing the perforations. This may be accomplished by holding the package in one hand and slitting one line of perforations with the thumb nail, after which the severed portion of the flap may be grasped and the remaining 10 perforations broken by pulling the flap outwardly.

When the match strip of Figure 8 with the cut-away base portion is employed, it will be appreciated that the rupturing of the perforations of the cover flap adjacent the abrasive 15 may be accomplished with great ease. Similarly when the opening 15 is elongated it is apparent that it will form a recess in which the finger nail will fit so that the perforations 20 can be readily broken.

After the perforations have been severed, the integral cover flap is pulled back and the matches may be readily procured and torn from the match strip. When the package is 25 provided with the removable portion 38 as shown in Figure 6, this portion of course, is entirely removed in a similar manner and may be thrown away.

After the integral cover flap has been 30 opened it may be secured in its closed position by means of the tabs shown associated therewith. With the cigarette package having the integral cover flap, a match strip provided with an opening 15 in the base thereof is employed. However by the use of the latch 34 shown in Figure 30 the opening in the base 35 may be omitted.

As is evidenced in Figure 2, the opening 15 is under the wrapper 2. To fasten the 40 cover flap in its closed position the tab provided therein is placed between the match strip and the wrapper 2 and inserted into the opening 15. As previously pointed out the opening for the tab may be provided 45 with either square cut sides or sloped sides. Moreover, instead of employing this design, a latch 34 of construction similar to that disclosed in Figure 30 may be positioned upon the outside of the package.

50 When the cigarette package itself is formed with an integral cover flap for the matches, the match strip is provided with no covering or with the short or full covering of protective material shown in Figures 23 or 24. 55 However, it is to be understood that by providing a plurality of openings in the match strip, as for example, a combination of the openings shown in Figures 8 and 9, the tab 60 construction used in connection with the covering of Figures 25 and 26 and the integral cover flap of Figures 3 and 4 may be employed. In this instance the tab of the 65 protective material would be inserted in one opening in the abrasive, while the tab of the

integral cover flap formed upon the wrapper itself would be inserted in the other opening in the base.

When the cigarette package is formed with the entirety removable portion 38 the match strip provided with one of the covers shown in Figures 25, 26, 28 and 30 may be employed to advantage. Thus the protective material forms a full cover for the matches and may be secured to the match frame so as to provide for a closure therefor after the removable portion 38 has been torn away. However, if desired, the covers of Figures 23 and 24 may be used or no cover whatever need be employed.

While many of the cigarette packages have been shown as provided with a match strip which is so constructed that when positioned between the wrappers of the package the matches are perpendicular to the lengthwise direction of the cigarettes, it is to be understood that a form of match strip such as that disclosed in Figure 19 wherein the matches run parallel with the lengthwise direction of the cigarettes may be employed. Instead of using the match strip having the two match units of Figure 19 it is to be understood of course, that a strip formed with a single match unit could be employed without departing from the spirit of the invention. Similarly the double match pads disclosed in Figures 20, 21 and 22 may be employed if desired.

In all of the constructions shown it will be appreciated that the match strips forming the subject matter of the invention afford a strong stiffener for the package. Particularly is this true when the match strip is provided with the hinged projections or hinged tabs of Figures 14 and 15. As is well known a cigarette package is usually carried loosely in the smoker's pocket and after opening as the number of cigarettes withdrawn therefrom is increased there is an increasing tendency for the remaining cigarettes to be crushed. Since each of the match strips effects a stiffener for the package, it will be appreciated that this disadvantage will be greatly reduced.

While the match strips have been shown as applied to cigarette packages only, it is to be understood that their use is not limited to this type of package, as obviously the match strip may be employed with other types of packages and containers for cigarettes as well as other articles or materials, as for example, with packages of smoking tobacco.

From the foregoing description it will be appreciated that I have provided a novel match strip and a method of directly associating the same with a cigarette package so that the matches thereof may be readily procured. At the same time a match strip possessing a construction allowing the formation of a neat and compact package which will lie and

stack evenly so as to facilitate handling has been designed. It will be further appreciated that by the incorporation of one of the match strips between the wrappers of the package 5 a stiffener therefor is provided which prevents serious crushing of the cigarettes.

While I have shown and described the preferred embodiment of my invention, I wish it to be understood that I do not confine 10 myself to the precise details of construction herein set forth, by way of illustration, as it is apparent that many changes and variations may be made therein, by those skilled in the art, without departing from the spirit 15 of the invention or exceeding the scope of the appended claims.

I claim:

1. In a cigarette package, an inner wrapper adjacent a plurality of cigarettes, an outer 20 wrapper surrounding the inner wrapper and a match strip secured between the two wrappers, the matches of said strip being positioned substantially perpendicular to the lengthwise direction of the cigarettes and the 25 heads thereof lying in a depression formed in the inner wrapper between two adjacent cigarettes.

2. In a cigarette package an inner wrapper adjacent a plurality of cigarettes, an outer 30 wrapper surrounding the inner wrapper and a match strip formed of a single piece of material secured between the two wrappers, said match strip having a base, top and sides, a plurality of matches positioned between the top and base with their ends formed 35 integral with the base, the base of said strip lying parallel with the longitudinal axis of the cigarettes and the match heads being positioned in a depression formed in the inner 40 wrapper between two adjacent cigarettes.

3. In a cigarette package a plurality of wrappers surrounding a plurality of cigarettes, a match strip secured between two of the wrappers, an integral cover flap formed 45 upon said outer wrapper adjacent said strip, said outer wrapper being provided with perforations so that the flap may be partially separated from the wrapper for swinging movement to uncover the matches, said flap being provided with a tab for maintaining it 50 in closed position after being partially separated from the outer wrapper.

4. In a cigarette package comprising a plurality of wrappers, a match strip having a base, top and sides bound between an outer and inner wrapper, said match strip being provided with an opening in its base, an integral cover flap formed upon the outer wrapper 55 adjacent the match strip, said wrapper being provided with perforations so that the flap may be partially separated from the outer wrapper for swinging movement to uncover the matches, the flap having a tab positioned thereon to engage the opening in said 60

base so that the flap may be maintained in closed position over the match strip after severance of the perforations.

In testimony whereof I affix my signature.
